UNITED STATES PATENT OFFICE.

JOSEPH B. BEACH, OF WEST MERIDEN, ASSIGNOR TO THE DERBY SILVER COMPANY, OF HUNTINGTON, CONNECTICUT.

DESIGN FOR CASTER-BOTTLES.

Specification forming part of Design No. **11,331**, dated August 12, 1879; application filed July 19, 1879.
[Term of patent 14 years.]

To all whom it may concern:

Be it known that I, JOSEPH B. BEACH, of West Meriden, in the county of New Haven and State of Connecticut, have invented a new Design for Caster-Bottles; and I do hereby declare the following, when taken in connection with the accompanying drawing and the letters of reference marked thereon, to be a full, clear, and exact description of the same, and which said drawing constitutes part of this specification, and represents side view.

This invention relates to a design for bottles for table-casters; and consists in the shape of the bottle as shown in the accompanying illustration.

The body A is square in horizontal section, and the sides of nearly equal width from top to bottom. The neck at a is polygonal in horizontal section, the sides of the polygon spring-

ing from the flat sides and angles of the body, curved inwardly, then outwardly to the rim or mouth b, as shown in the accompanying illustration.

Around the body in horizontal lines are two series of beads, d, but neither these beads nor the stopper are necessary to this design, the essential features of which are the square body and vertically-curved polygonal neck, as shown.

I claim—

The herein-described design for caster-bottle, consisting of the square body and polygonal vertically-curved neck, as shown in the accompanying illustration.

JOSEPH B. BEACH.
